PENDANT CHARM

Henry B. Lederer, 120 Bay Blvd., Atlantic Beach, N.Y.

Filed May 21, 1963, Ser. No. 75,000

Term of patent 7 years

(Cl. D45—17)

FIG. 1

FIG. 3

FIG. 2

FIG. 4

FIG. 1 is a face view of one side of my pendant charm; FIG. 2 is a similar view of the opposite side of said charm;

FIG. 3 is a side elevational view from the right of FIG. 1;

FIG. 4 is a fragmentary view in perspective of the lower right hand leaf, bearing the horseshoe ornament embedded in its upper surface, of the four leaf clover design shown in FIG. 1.

I claim:

The ornamental design for a pendant charm, as shown.
